TREATMENT OF RESIDUAL OILS

William H. Carmody, Pittsburgh, Pa., assignor to
The Neville Company, Pittsburgh, Pa., a corporation of Pennsylvania

No Drawing. Application November 3, 1936,
Serial No. 108,963

3 Claims. (Cl. 196—78)

This invention relates to the treatment of still residues recovered in the purification and refining of light oils obtained in the operation of by-product coke ovens, and a major object of the 5 invention is to provide a simple, efficient and easily performed method of converting such material into products of greater utility.

The term "pure still residues" as used herein has reference to material recovered from still residues produced in the recovery of coke oven light 10 oils. In the high temperature carbonization of coal in by-product coke ovens the common practice is to scrub out the light oils from the gases with a high boiling petroleum wash oil thus producing a solution of the aromatic light oils in 15 the wash oil. This is then distilled to give a mixture of light oils, chiefly benzol, toluol, xylol, and solvent naphtha, which mixture is then fractionated to obtain the individual constituents 20 somewhat impure cuts of rather narrow boiling range.

The crude fractions, or cuts, are then commonly acid washed by vigorously agitating them with a small amount of strong sulfuric acid, 25 which polymerizes the unsaturated constituents and produces a mixture of high boiling oils and resinous bodies, and because the temperature is not controlled in this step, rise in temperature may cause other reactions to take place with formation of other oils and resins. After separation 30 from the sulfuric acid stratum, the oil is then washed with alkali, to neutralize acid, following which it is distilled to produce commercially pure solvent, leaving in the still a residue 35 of a mixture of the polymers and high boiling oils referred to. Commonly sufficient solvent is left in the residue to permit it to be removed from the still and handled in the liquid state.

These residues of polymers and high boiling 40 oils from the various cuts are then combined and subjected to distillation to strip out all of the content of solvent oil, such as benzol and the like. The residue from this operation forms what is known in the trade as pure still residue. It comprises chiefly polymers of unsaturated compounds, appearing chiefly as resins, and other reacted bodies appearing as high boiling oils. Resolution of this mixture into its individual components has not been possible heretofore, at least 45 by ordinary or commercially practicable means, and the material has been of low market value, being either disposed of conveniently by adding it to coke oven tar, or burned as a fuel, for lack of a more profitable mode of handling it.

50 In my copending application Serial No. 85,747,

filed June 17, 1936, I have disclosed and claimed a process of treating such pure still residue for the recovery of products of increased value. According to that process the still residue is steam distilled, for instance at 300° C., to strip it of 5 its content of high boiling oils. Thereby there is obtained a distillate consisting of the oils and water, and a resinous residue. The oil in the condensate is separated from the water, preferably by heating the mixture almost to the boiling 10 point of water, and allowing it to stand for settling, following which the water is drawn off from the supernatant oil layer. The oil is then heated somewhat above the boiling point of water, say to a temperature above 100° and not exceeding 15 about 150° C., whereupon the residual water in the oil distills off together with a small amount of low boiling light gravity distillate.

The oil remaining in the still is now dry and may be fractionated, suitably after addition of 20 caustic soda in an amount at least sufficient to combine with free acid contained in the oil. The distillation is carried out at atmospheric pressure, or under slightly reduced pressure. The distillate may be separated into more or less 25 definite cuts having useful solvent action. For instance, in treating still residue from one source the cut boiling from 150° to 200° C., which may amount to about 10 per cent of the oil, has a sharp characteristic odor resembling that of benzol fore-runnings or cyclopentadene; this may be considered a crude solvent naphtha. A second cut boiling from 200° to 250° C. affords a light 30 amber colored oil which possesses a characteristic odor that can be described as sour or musty. It is lighter than water, from which it separates 35 readily, and it may amount to about 15 per cent of the original oil. The properties of this oil are similar to those of the cut boiling from 275° to 300° C., constituting about 60 per cent of the 40 original dry oil, which has a specific gravity of about 0.98, and an aniline point of 26° C., indicating that the oil is of aromatic character and of high solvent power. Finally, there is obtained a cut boiling from 300° to 360° C., which is rather 45 viscous and constitutes about 15 per cent of the original dry oil. Above 360° C. decomposition occurs.

The aniline points referred to herein were determined in accordance with the method used 50 by The Neville Company, of Pittsburgh, Pa. In accordance with this method there is prepared a test mixture by weighing into a small flask, say of 100 to 125 ml. capacity, 10 grams of the material whose aniline point is to be determined and 55

20 grams of a standard petroleum benzine diluent. The two materials are mixed thoroughly and 2.5 ml. of the test mixture are pipetted into a test tube of about $\frac{3}{4}$ or $\frac{7}{8}$ inch diameter and 6 or 7 inches in length into which there has been placed 5 ml. of freshly distilled reagent quality aniline, which should be of pale yellow color. Into the mouth of the test tube there is placed a vented cork stopper carrying a thermometer having a suitable scale, say minus 30° C. to plus 50° C. The thermometer is adjusted so that the bulb is completely covered by the solution but does not quite touch the bottom of the test tube. The mixture is then warmed gently with constant agitation until it becomes entirely homogeneous. It is then cooled slowly and carefully with constant agitation until the solution becomes just sufficiently cloudy to obscure the outline of the thermometer bulb. This temperature is recorded. There is then added an additional 0.5 ml. of the test mixture, and this procedure repeated. The addition of 0.5 ml. of the test mixture is repeated until a maximum temperature of clouding has been reached, and the cloud point begins to drop. The maximum temperature of clouding is taken as the aniline point, and usually three 0.5 ml. additions of the test mixture will be sufficient. The standard petroleum benzine diluent is made from industrial pure toluol and a low boiling petroleum naphtha known as petroleum benzine; its specific gravity is usually 0.725 to 0.730, and it distills completely between about 85° C. and 125° to 130° C. A mixture of these two in the proportion of approximately 92 per cent of petroleum benzine and 8 per cent of toluol is prepared. This is then standardized against industrial pure toluol by the foregoing procedure. Toluol should show an aniline point by this procedure of exactly 21° C. In case the standard diluent fails to do this the proportions must be varied until the standard diluent shows an aniline point of 21° C. If the mixture as prepared has an aniline point lower than 21° C., the percentage of petroleum benzine must be raised, while in case the aniline point is above 21° C., the percentage of toluol is to be increased.

50 The various fractions thus obtained from pure still residue possess solvent properties which render them more valuable as an article of commerce than the original still residue. Also, the resin resulting from steam distillation in an amount of 40 per cent of the still residue in the case of material from one source, possesses properties making it desirable for various uses, as described more fully in my aforesaid application.

55 My investigations have shown that the oils isolated by steam distillation of pure still residue, as just described, are highly stable. They appear to be of saturated character, and sulfuric acid and aluminum chloride do not polymerize them. They are stable to heat, and they do not decompose when distilled at atmospheric pressure. The various cuts produced upon distillation appear to be mixtures of oils, rather than simple individuals.

60 I have now discovered, and it is upon this that the present invention is predicated, that the oil recovered from pure still residues in the practice of my aforesaid invention may be treated in another manner to produce simple aromatic oils for which there is a constant demand and which are of material commercial utility and value. More specifically, I have found that by heating and catalytically cracking the pure still residues

there is produced a mixture of simple aromatic oils, such as benzol, toluol, xylol and solvent naphtha, which may be recovered and easily separated by distillation and fractionation, together with a new resinous material.

65 In the preferred practice of the invention the pure still residues or a fraction thereof is heated moderately in the presence of a cracking catalyst, most suitably a metallic chloride cracking catalyst, examples being aluminum chloride and ferric chloride. Thereby the pure still residue is easily and rapidly broken down with production of unsaturated units and active hydrogen. Some of the unsaturated substances thus produced become polymerized in the presence of the catalyst, with production of a resinous material, while others become hydrogenated with a comparatively small amount of hydrogen to produce well-defined and valuable aromatic solvents, chiefly benzol, toluol, xylol and solvent naphtha. Some 10 of the uncracked constituents appear to become hydrogenated, producing oils resistant to cracking.

70 As exemplifying the practice of the invention reference may be made to its application to the 275° to 300° C. cut of pure still residue as described in connection with my aforesaid invention. This material was mixed with anhydrous aluminum chloride in the proportion of 500 cc. of oil to 25 grams of catalyst, and the mixture 75 of the two materials was then slowly and progressively warmed in a still, the vapors evolved being withdrawn from the still and condensed. The condensed liquid was found to be a mixture of benzol, toluol, xylol and solvent naphtha, with little or no content of other substances. During this run benzol first appeared when the temperature of the liquid in the still was about 75° C., toluol when the liquid temperature was about 110° C., and xylol when the liquid was at 140° C. 80 At a temperature in the cracking mixture of 250° C. the cracking and distillation were apparently complete.

85 It thus appears that the cracking not only takes place readily, but also that it occurs at low temperatures, apparently at or below the boiling points of the aromatic oils produced, which is 45 advantageous as will be recognized by those concerned with this art.

90 The distillate was carefully washed with sodium hydroxide to eliminate hydrochloric acid, followed by washing with water and drying. It was then carefully refractionated with production of a cut boiling between 45° and 1230° C., and consisting mainly of benzol and toluol. This mixture 95 amounted to about 17 per cent of the total distillate obtained in refractionation, and it had a specific gravity of 0.874 at 15.5°, and an aniline point of 25° S. The next cut boiled between 120° to 150° C.; it consisted chiefly of xylol and amounted to about 54 per cent of the redistilled 100 material. Its specific gravity at 15.5° C. was 0.87, and its aniline point was 21° C. The last cut boiled from 150° to 208° C., had an aniline point of 24° C., and was chiefly solvent naphtha.

105 After the cracking operation has been completed there remains in the still a substantial proportion of a resinous material and uncracked oil. The aluminum chloride may be settled, and the resinous material and uncracked oil removed. In the case of the material referred to it amounted to 12 to 15 per cent, based on the original still residue. The resin recovered in the foregoing test was dark brown, hard and brittle, and its melting point was about 75° C. Its color may be made 75

somewhat lighter by treatment with alkali, say 5 soda ash. It is useful for the purposes to which 10 resins are applied. I now believe that the un-cracked oil resulted from hydrogenation of one or more constituents of the original pure still residues, with production of materials resembling cyclic paraffins. This is indicated by its aniline point of 38° to 40° C. which coupled with its high 15 boiling point indicates a loss of aromatic nature. 20 The original pure still residues used had an aniline point of 26-27° C., while a petroleum oil of the same boiling point has an aniline point of about 50° C.

Various modifications in the practice of the 25 process will occur to those skilled in the art. For instance, the mixture undergoing cracking may or may not be agitated. My tests have shown that in this manner the proportions of the simple aromatic oils recovered from the 30 cracking operation may be varied although agitation does not have any substantial effect upon the total amount of oils recovered. Thus, rapid agitation, with consequent more intimate contact of oil and catalyst, increases somewhat the 35 amount of benzol and toluol recovered, at the expense of xylol. On the other hand, agitation produces less coke and residue adhering to the walls of the still, but it increases the content of un-cracked oil.

30 My tests have shown further that when aluminum chloride is used, coating of the catalyst by resin or the like so slows down the rate of cracking that less than about 2 per cent of catalyst ordinarily will not produce economically satisfactory results. On the other hand, increasing 35 the amount of catalyst up to about 7 per cent progressively increases the yield of solvent, as appears from the following tabulation representing data obtained in the practice of the invention applied to 500 cc. portions of the dried distillate, recovered by steam distillation of the still residue, as described above:

		AlCl ₃ used								
		2%	3%	4%	5%	6%	7%	8%	9%	
Total volume of aromatics recovered, c. c.		70	100	150	155	195	238	238	240	
I. D. °C.	92	90	88	81	81	76	76	73		
To 90° C. c. c.	0	0	0	1	1	2	2	2		
To 105° C.	1	2	2.5	2	2.5	11	9	14		
To 120° C.	3	3.5	5	12	17	43	43	42		
To 130° C.	7	17	28	32	48	58	65	67		
To 150° C.	34	68	108	125	152	184	188	188		
To 160° C.	38	73	117	129	162	188	192	195		
To 170° C.	41	76	121	134	168	197	200	200		

55 From the table it will be seen that the maximum yield is reached at about 7 per cent of aluminum chloride; greater amounts do not substantially increase the yields and thus serve merely to increase costs. Moreover, the data show how amounts from 2 to 7 per cent lower the temperature at which cracking begins, which is of further advantage, as will be recognized by those skilled in the art.

60 When ferric chloride is used as the catalyst the total yield of aromatic solvents and of resins is lower, and the yield of un-cracked oil is higher, showing how the character of the result may be varied according to the product desired.

65 In the practice of the invention I may treat the composite pure still residues obtained by the method described in my above-identified patent application or, if desired for any reason, the

pure still residues may be fractionated in the manner referred to above, and any one or more of the cuts may be subjected individually to cracking. Also, the pure still residue from any of the individual light oil fractions may be treated in accordance with my aforesaid invention to produce an oil for treatment in accordance with the present invention. All such materials are contemplated by the term "pure still residues" as used herein. By such selection of starting material the proportion of simple solvent oil produced in the practice of the invention may be varied according to need. This is indicated by the following data obtained in actual practice of the present invention:

5

10

300-360° Cut**	2	2	35	12

* Residue of coke oven light oil recovery.

** Fraction produced by treatment of total still residue according to my copending application.

According to the provisions of the patent statutes, I have explained the principle of my invention and have described what I now consider to represent its best embodiment. However, I desire to have it understood that, within the scope of the appended claims, the invention may be practiced otherwise than as specifically described.

30 I claim:

1. That method of treating high boiling oils 40 contained in pure still residues resultant from fractionation of the cuts of coke oven light oils which comprises heating a mixture of said high boiling oils and at least about 2 per cent of aluminum chloride to a temperature not substantially over about 265° C., and thereby producing a mixture of simple aromatic oils, such as benzol, 45 toluol, xylol and naphtha, and a resinous material.

2. That method of treating high boiling oils 50 contained in pure still residues resultant from fractionation of the cuts of coke oven light oils which comprises heating a mixture of said high boiling oils and at least about 2 per cent of a cracking catalyst of the group aluminum chloride and iron chloride to a temperature not substantially over about 265° C., thereby producing a 55 mixture of simple aromatic oils, such as benzol, toluol, xylol and naphtha, and a resinous material, distilling off said simple aromatic oils, and recovering said resinous material.

3. That method of treating high boiling oils 60 contained in pure still residues resultant from fractionation of the cuts of coke oven light oils which comprises fractionating said high boiling oils to recover that cut distilling between about 275° to 300° C. at atmospheric pressure, and heating a mixture of said cut and at least about 2 per cent by weight of aluminum chloride progressively to a temperature not substantially over about 265° C., and thereby producing therefrom a mixture of simple aromatic oils, such as benzol, toluol, xylol and naphtha, and a resinous material.

WILLIAM H. CARMODY.

Certificate of Correction

Patent No. 2,143,474.

January 10, 1939.

WILLIAM H. CARMODY

It is hereby certified that errors appear in the printed specification of the above numbered patent requiring correction as follows: Page 2, second column, line 54, for "1230° C." read 120° C.; line 59, for "25° S." read 25° C.; page 3, second column, lines 15 to 20 inclusive, strike out the heading to the table and insert instead the following:

Original oil	Product, percent			
	Benzol	Toluol	Xylo	Solvent naphtha

and that the said Letters Patent should be read with these corrections therein that the same may conform to the record of the case in the Patent Office.

Signed and sealed this 14th day of March, A. D. 1939.

[SEAL]

Henry Van Arsdale.

Acting Commissioner of Patents.
